BULLDOZER

Frank H. Lamb, Hoquiam, Wash.

Application February 6, 1933, Serial No. 655,495

17 Claims. (Cl. 37—144)

This invention relates to dirt moving machines, and it has reference more particularly to motorized machines now generally known in trade as "bulldozers" or "trailbuilders" and which are designed primarily for the moving of dirt by blade action such as in grading, ditching, leveling and filling, but which are applicable to various other uses and operations with a like amount of satisfaction.

- 10 As a matter of explanation, and to give a better understanding of the novel features of the present construction, it will here be stated that the earlier types of bulldozers consisted of a rigid blade supported in front of a tractor, with means whereby the blade might be raised to dump the load or to adjust it when cutting in too deeply. Due to the construction of the conventional tractor, it has been a difficult matter to attach the bulldozer to the tractor. In some types of machines the tractor is completely encircled by the bulldozer frame which takes the pushing thrust and which is attached to the rear of the tractor at the towing hitch. In some makes, the thrust is taken by brackets attached to the track frames. 25 In practically all makes, owing to difficulty of attachment, the bulldozer is a heavy and expensive attachment.

It is also to be pointed out that in earlier day, as well as in those present day types of bulldozers that are applied to tractors of the track laying types, the long distance of the blade from the center of oscillation of the tractor multiplies the up and down motion of the blade as the tractor passes over uneven ground and this necessitates constant attention, and adjustment by the operator, and at best leaves an uneven, wavy grade.

It is the principal object of the present invention to provide a novel bulldozer equipment for a tractor of the crawler or tracklaying type, that has greater dirt moving capacity, with less upkeep and better adjustment than heretofore has been available. Furthermore, to provide an improved type of bulldozing, or dirt moving machine, adapted to all kinds of dirt moving operations that may be encountered in road building, grading, filling, ditching or similar work, and which utilizes a tractor of the track laying type as the motive and power supplying means, and which is equipped with a blade of novel form having independent, opposite end sections; the blade also being supported from the tractor frame in a manner permitting of its being raised or lowered bodily, or tilted laterally to cause one end to be lowered and the other raised, as well as pro-

viding for independent angular adjustment of the opposite end sections for the purpose of casting to either side of a roadway or to both sides, or to retain the load therein for straight ahead movement.

It is also an object of the invention to provide a machine as above stated in which the bulldozer equipment is supported by short bracketed connections relatively close to the sprocket center, or center of oscillation of the tractor, thereby reducing to a minimum the oscillation of the blade by reason of travel on uneven roadways and also gaining advantage of the weight of the heaviest part of the tractor for crowding in the cutting blade for uprooting rocks, stumps, and for working in heavy, sticky clay or gumbo soils.

It is also an object of this invention to provide easily controlled power means for effecting the various tilting and vertical adjustments of the blade. Also to hinge the opposite end sections of the blade to a central pivoted support for easy angular adjustment, and to provide for separate and independent angular adjustment of the blade sections.

Another object is to provide novel hydraulic power means for bodily raising and lowering the bulldozer equipment relative to the tractor, and to provide a separate hydraulic means on the bulldozer operable at will and while the machine is in motion for effecting the lateral tilting adjustments of the blade.

Another feature of the invention resides in the provision of a parallel link connection between the tractor frame and blade support which effects an upward and downward adjustment of the blade without change in its vertical inclination and which provides for applying a substantial part of the weight of the tractor to the blade in crowding it into the ground for heavy work.

Other objects of the invention reside in the details of construction of the various parts, in their combination and mode of operation, as will hereinafter be described.

In accomplishing these and other objects, I have provided the improved details of construction, the preferred forms of which are illustrated in the accompanying drawings, wherein—

Fig. 1 is a side elevation of a bulldozer mechanism embodying the present invention.

Fig. 2 is a perspective view of the rear end portion of the tractor chassis or frame structure showing the supporting lugs to which the bulldozer mounting brackets are to be hingedly attached.

ing and tilting bar, and the adjusting shaft associated therewith.

Fig. 4 is a diagrammatic view of the pump and control system for the two hydraulic cylinders.

Fig. 5 is a plan or top view of the machine, as illustrated in Fig. 1.

Fig. 6 is a front elevation of the blade mechanism.

Figs. 7, 8, 9 and 10 are views, in plan, illustrating various angular positions to which the blade sections may be adjusted.

Fig. 11 is a plan view of a modified form of equipment.

Fig. 12 is a side view of the same.

Referring more in detail to the drawings—

In its preferred construction, the present machine utilizes a tractor of the track laying type as the moving and power supplying medium. Preferably this tractor is of that kind described and illustrated in connection with the dump body mechanism of my pending application filed February 5, 1932, under Serial No. 591,072. Such a tractor, when used for the present purpose, should be equipped with an engine of horsepower adequate to carry on the work to the best advantage and in addition, to furnish what power is necessary for operation of the blade adjusting means.

As herein illustrated, the tractor is designated in its entirety by reference numeral 1. It has a main frame, or chassis, seen best in Figs. 5 and 11, comprising opposite side beams 2—2 and suitable cross connections as at 3, joining them when needed. At their rearward ends, the opposite side beams 2—2 are rigidly secured to a heavily built, and substantial gear case 4 within which the power transmission gearing and various controls through which the tractor is driven, are housed. Extending longitudinally of the chassis, at opposite sides, are the track mounting frames 5—5. These frames have their rearward ends pivotally mounted for oscillation on the opposite ends of a substantial shaft 6 that extends transversely through the case 4 as a support for that end of the chassis. At their forward ends the track frames support the chassis through the mediacy of spring suspensions of suitable form, as designated at 7 which permits the necessary movement vertically of the track frames with respects to each other and to the main frame, required to accommodate the tracks to travel over uneven surfaces without detrimental strain on the various mountings.

Tracks 8, of continuous, flexible belt construction are mounted for travel about the frames 5—5 on wheels 9 and 10 at opposite ends of the frames; the wheel 9 at each side being a driving sprocket for the track at that side. Between wheels 9 and 10, the lower runs of the tracks are guided by and operate against idler wheels 11 carried on the frames, while the upper runs are supported by idlers 12 also mounted by the frames.

The driving sprockets 9 for the tracks are mounted at the outer ends of differential axles 14—14 which are driven through the mediacy of transmission mechanism of a suitable nature indicated at 15 in Fig. 5, which in turn has connection through the main drive shaft 16, and change speed gear mechanism 17 with the vehicle engine 18 mounted at the forward end of the chassis. The transmission mechanisms 15 and 17, while not illustrated, provide for the operation of the vehicle in opposite directions and at various speeds and the guiding and turning of the

vehicle is accomplished by driving the tracks at the same or at different speeds.

At the forward end of the chassis, and at one side of the engine, is a cab 20 for the operator who, from this location, through manipulation of suitable controls, operates both the tractor and the bulldozer equipment.

The bulldozer equipment is mounted at that end of the frame which, for convenience, is termed the rear end; this being the end opposite the engine and operator's position. This equipment is connected directly to the rear end wall 4a of the heavy gear case 4, which is a part of the chassis or frame structure, through the medium of two heavily constructed brackets 21 and 22 of triangular form as seen in Fig. 5. These brackets are substantially alike in construction and are provided at opposite sides of their base ends with hinge lugs 23 disposed between paired lugs 24 fixed on or integral with the rear end wall of the gear case and hingedly secured therein by pivot bolts 25, so as to permit of an upward and downward swinging movement of the outer ends of these brackets.

In normal use, the two brackets are disposed substantially in horizontal position, and are vertically spaced, as seen in Fig. 1, and are of substantially the same length. At their swinging ends each bracket terminates in a hinge lug and these are connected by pivot bolts 26 and 27, respectively, as in Fig. 1, with upper and lower end portions of an upright channel beam 28 which is a part of the blade mounting head. This beam, as presently described, supports the blade, and is vertically movable to bodily raise or lower the blade by the upward or downward swinging action of the supporting brackets on their hinge mountings. To effect this movement of the brackets, I have fixed a lever arm 30 to the upper bracket and this extends in an upward and forward direction and is connected pivotally at its ends as at 31, with a link 32 which, at its opposite end, is pivotally attached, as at 33, to a cross head 34 reciprocally movable in a horizontal guide 35 that is rigidly fixed upon the gear case 4 in the central longitudinal line of the vehicle. This cross head is attached to the outer end of a piston rod 36 which is actuated by a piston 37 in a hydraulic cylinder 38 fixed to and continuing from the forward end of the guide 35. Action of the piston in opposite directions as presently described, effects a corresponding movement of the cross head 36 and a consequent raising or lowering of the beam 28 by reason of the swinging action of bracket 21.

It is to be pointed out, that by reason of the parallel relation of the brackets 21 and 22 and their being substantially equal in extent, the motion produced is substantially a parallel link movement which retains the beam 28 in a vertical position for different positions of vertical adjustment, and this is important as it provides for the vertical adjustment of the blade without changing its angle of inclination relative to the ground.

Disposed along the forward face of the beam 28 is the blade mounting bar 40. This is pivotally attached at its lower end to beam 28 by a pivot pin 41 which permits the upper end of bar 40 to be swung laterally in opposite directions. The bar 40 is provided on its forward face, as seen in Fig. 3, with forwardly extending brackets 42 mounting a vertical hinge pin 43 therein, and on this pin the opposite end sections 75

44—44' of the blade are hingedly mounted. The two blade sections are alike in construction and of equal extent. Each consists of a welded sheet metal plate suitably curved to promote a rolling action of the material pushed ahead of it, and is equipped on its back side with suitable stiffening ribs 45 and at its inner end with mounting lugs 46 receiving the hinge pin 43.

The hinge pin mounting permits of swinging adjustment of the blade sections to various angular positions transversely of the tractor as is clearly shown in Figs. 7 to 10 of the drawings. After an adjustment has been made, the blade sections are held in set positions by bracing struts 58—58' located at opposite sides of the tractor. These struts have ball and socket connections 51 at their outer ends with the outer ends of the blade sections, and are slidably adjustable in guides 52 mounted by ball and socket connections 53 on the ends of the cross shaft 6 which supports the track frames. Lock bolts 54 are applied to the guides and through holes provided in the struts to retain the adjustment. Thus the entire pushing strain applied through the blade mountings is taken directly by the tractor frame and not by the track frames or any draw bar connection.

For lateral tilting of the blade, the bar 40 is swung laterally on the pivot 41 to one or the other side of the upright beam 28. To control this movement I have mounted a hydraulic cylinder 65 rigidly on the upper end of beam 28 and transversely of the vehicle. This cylinder contains a piston 66 fixed on a piston rod 67 that extends from opposite ends of the cylinder. A shifting slide 68 for the bar 40 is arranged parallel with the piston rod, forwardly of the cylinder and is longitudinally shiftable in supports 69—69' extending from the cylinder ends. The rod 68 has fixed connections 70—70 at its opposite ends with the piston rod and, at its center, mounts a block 72 with a pivot pin 73 extended forwardly therefrom into a vertical slot 74 in the upper end of beam 40. Reciprocal movement of the piston 66 is controlled by the manipulation of a control valve mechanism, presently described, operable from the driver's position; and by an application of pressure medium to one or the other end of the cylinder, the rod 67 will be actuated accordingly to adjust the lateral inclination of the blade to a desired position under control of the valve control.

To protect the hinged connections of the two blade sections 44—44' with the blade head bar 40, I provide vertical V-shaped hardened steel prow 78 rigidly fixed to the forward ends of the brackets on the blade head bar 40. This prow forms a colter in digging and materially assists in holding the bulldozer to a straight course in breaking up hard soils or in digging out roots and obstructions.

In connection with the hydraulic cylinder 38 for lifting or lowering the blade head, I provide a hydraulic pump 80 driven by its shaft 81 from suitable power take off, not shown, from the main drive shaft. This pump, as disclosed, diagrammatically, in Fig. 4 is operable to pump a liquid pressure medium from one end of the cylinder to the other to thereby adjust the position of the piston to raise or lower the blade head and to hold it rigidly at the adjusted positions. To give control to the piston, opposite sides of the pump are connected to opposite sides of a four way valve housing 82 by pipes 83 and 84 which housing, in turn, has upper and lower outlets with

pipe connections 85 and 86 to opposite ends of cylinder 38. The valve casing 82 contains a four way valve plug 87 rotatably adjustable by lever 88 to control the direction of flow of liquid. Lever 88 is connected by link 89 with a hand lever 90 adjacent the operator's position. There are also pipe connections 92 and 93 between the opposite outlets of pump 80 and opposite sides of a four way valve housing 94 which has upper and lower pipe connections 95 and 96 leading to opposite ends of the cylinder 65. The valve housing 94 contains a four way plug 97 rotatable by lever 98 to control flow of pressure medium into and from opposite ends of cylinder 65 thereby to adjust and maintain any adjustment of the piston for holding the blade at different tilted positions. The lever 98 has a link 99 leading to a control lever 100 adjacent the operator's seat.

In Figs. 11 and 12, I have illustrated an alternative, or modified construction applicable to the tractor frame in substantially the same manner as before described and operated up and down by the hydraulic cylinder 38 and its associated mechanism, but having no angular adjustment. This modified construction comprises a single piece blade 101 set at a right angle to the longitudinal direction of the vehicle and hingedly attached to the rear end lugs 24 of the case 4 by an upper bracket 21a and by a pair of lower end brackets 102—102. The upper bracket 21a is attached to the base 4 as is the bracket 21 of the construction previously described and is hingedly attached at 103 to the central upper part of the blade. The brackets 102—102 are attached at their inner ends to the lower sets of lugs at opposite sides of the gear case 4 and at their outer ends are attached as at 105 to the blade adjacent its lower edge. Up and down action of the blade is effected exactly as in the other device by connection with the cross head 34 actuated by the piston rod 36 of hydraulic cylinder 38.

In using the bulldozer of Figs. 1 to 10, the blade is adjusted to the desired depth by action of the hydraulic cylinder 38 under control of valve 87. For land clearing, surface leveling and grading, under some conditions both ends of the blade are set at right angles to the road. When it is desired to side cast from a fill, or to throw up a fill from ditches or sides, both ends of the blade are set at appropriate angles across the road as in Figs. 7 and 8 and secured by the bracing struts 50—50'. To vary the lateral inclination of the blade for ditch digging this is effected by the mechanism of the hydraulic cylinder 65 under control of valve 97. When it is desired to push as large a load as possible, both blade sections are set forwardly, as in Fig. 9, forming a wide V which increases the holding capacity to a material extent.

The shape of the blade, which I have adopted, also tends to roll the load toward the center instead of around the end of the blade.

When it is desired to level a crowned fill, the outer ends of the blade can be set backward from the center as in Fig. 10 forming a wide plowing V which will cast the dirt to both sides. In this position the blade may be used as a snow plow with good satisfaction.

The advantages to be gained by the present construction are many. Those most apparent are: a wide range of adjustability of the blade sections; the rigidity of the construction and the application of thrust only to the frame structure of the tractor; the short connection between the blade and tractor, which reduces blade oscillation to a minimum; the possibility of applying the

greater part of the weight of the tractor to the blade to crowd it into the ground; the vertical adjustment of the blade without change in its angle relative to the ground; the ease of detachment of the equipment when it is desired to use the tractor for other purposes; and the comparatively low cost of producing the equipment.

Having thus described my invention, what I claim as new therein and desire to secure by Letters Patent is—

1. A machine of the character described comprising a tractor having a rigid frame, a plurality of brackets in substantially parallel, vertically spaced planes, hingedly connected at their inner ends to the frame, a blade head having pivoted supporting connections with the outer ends of the brackets, a blade adjustably mounted by the head and movable to different angular positions thereon relative to the direction of travel and means for effecting an adjustment of the brackets for changing the elevation of the blade.

2. A machine of the character described comprising a tractor having a frame structure, brackets vertically spaced and hingedly attached to the frame to extend from one end thereof and adapted for up and down swinging movement at their outer ends, blade mounting means having spaced pivotal connections with the swinging ends of said brackets, a blade adjustably mounted on said mounting means and mechanism on the tractor operable to hingedly adjust the brackets to raise or lower the blade mounting means and for rigidly retaining an adjustment thereof.

3. A machine of the character described, comprising a tractor having a rigid frame, a pair of brackets vertically spaced, and with ends hingedly attached to an end wall of the frame, an upright blade head, means pivotally connecting the outer ends of said brackets with the blade head in spaced relation corresponding substantially to that of their inner ends, a blade mounted by said blade head and means attached to the frame and to one of the brackets for effecting adjustment of the latter for raising or lowering the blade.

4. A machine of the character described comprising a tractor having a rigid frame, vertically spaced brackets with their inner ends hingedly attached to the said frame for movement about horizontal axes; said brackets being adapted for vertical adjustment at their outer ends, a blade head having vertically spaced pivoted connections with the outer ends of said brackets, a blade mounted by said blade head and adjustable thereon to different angular positions transversely of the tractor and means on the tractor for adjusting the brackets for raising or lowering the blade.

5. A machine of the character described comprising a tractor having a rigid frame structure, a pair of blade mounting brackets, vertically spaced and having their inner ends hingedly attached to the tractor frame, a blade head having spaced, pivoted connections with the outer ends of said brackets and supported through said connections, a blade adjustably attached to the head, and extending laterally to opposite sides thereof, and bracing struts extended between the ends of the blade and tractor frame.

6. A machine of the character described comprising a tractor having a rigid frame structure, upper and lower blade mounting brackets hingedly mounted on the frame to extend at one end thereof in the direction of travel, a blade mounting head having spaced pivotal connections with the outer ends of the said brackets, a blade pivotally mounted by said head and adjustable on

its mounting to different angular positions transversely of the tractor, means on the tractor connected with one of said brackets for raising or lowering the blade head and for retaining its adjustment, and struts pivotally fixed to the outer ends of the blade and to the tractor frame at opposite sides for bracing the blade.

7. A device as in claim 6 wherein the blade has pivotal adjustment on the head about a horizontal pivot and a vertical pivot, and wherein the struts have universal connections with the blade ends and with the tractor frame.

8. A machine of the character described, comprising a tractor having a rigid frame structure, vertically spaced blade mounting brackets with ends hingedly attached to an end of the frame at opposite sides; said brackets having their outer ends disposed in the medial longitudinal plane of the tractor, an upright blade head having correspondingly spaced pivoted connections with the outer ends of the said brackets, a blade mounted by said head and extending laterally thereof to opposite sides of the tractor, an actuating lever arm on one of said brackets, and power mechanism mounted on the tractor and rigidly connected with the said lever arm for hingedly adjusting the bracket to raise or lower the blade head and for retaining it at different working elevations.

9. A machine of the character described comprising a frame having an end wall, a pair of brackets of triangular form, horizontally disposed and vertically spaced and having hinged connections at opposite ends of their base portions with the said end wall, the outer ends of said brackets being vertically aligned and vertically movable, a blade head pivotally connected with the outer ends of said brackets to maintain them in parallel relation, a blade on said head, a lever arm fixed to the upper bracket and extended upwardly therefrom, a hydraulic cylinder fixed on the tractor, a piston operable therein, a piston rod, an operating connection between the rod and lever and means for controlling an application of pressure medium to the cylinder for actuating the piston.

10. The combination with a tractor of the track laying type having a frame, a cross shaft supporting the frame at one end, track frames and tracks mounted by opposite ends of said shaft, of a bulldozer mechanism comprising upper and lower brackets hingedly attached to the said frame to extend in the direction of travel from that end supported by said shaft, to swing vertically at their outer ends, a blade pivotally connected with and functionally mounted by said brackets at their outer ends, and means fixed on the tractor frame and operatively connected with the brackets for positively adjusting the depth or elevation of the blade and providing a rigid connection between the frame and blade whereby weight of the tractor may be applied to the blade.

11. In a machine of the character described, a tractor, a blade head supported from the tractor frame at one end thereof, an upright bar pivotally attached to said head to swing thereon toward opposite sides of the tractor, a blade mounted by said bar to extend laterally of the tractor and means on the head operatively connected with the bar for effecting and retaining lateral adjustments of the bar.

12. In a machine of the character described, a tractor, a blade head supported from the tractor at one end thereof, an upright bar pivotally attached to the head for lateral swinging in oppo-

- site directions, a blade mounted by the bar and extending transversely of the tractor, a hydraulic cylinder fixed on the head, a piston operable in the cylinder and having operative connection 5 with the movable end of said bar, and means for controlling application of pressure medium to the cylinder for moving the piston.
13. In a machine of the character described, a tractor, a blade head supported from the tractor at one end thereof, means on the tractor for adjusting the head vertically, a bar pivotally attached at its lower end to the head to swing laterally at its upper end to opposite sides of the head, a blade mounted by said bar and extending transversely of the tractor, a horizontally disposed hydraulic cylinder fixed on the head transversely of the tractor, a piston in the cylinder, a piston rod extended from opposite ends of the cylinder and having connection at its ends with the swinging end of said bar, and means for controlling an application of pressure medium to the cylinder to move the piston to adjust the bar and blade accordingly.
14. In a machine of the character described, a tractor having a frame, a blade head adjacent one end of the frame, brackets hingedly attaching the head to the tractor frame for vertical adjustment, a blade mounting bar pivotally attached at its lower end to the head to swing laterally in opposite directions at its upper end, a blade mounted by said bar transversely of the tractor, a hydraulic cylinder fixed on the tractor frame including a piston and piston rod, having operative connection with the brackets to raise and lower the blade head, a hydraulic cylinder fixed on the blade head and including a piston and piston rod having operative connection with the bar to swing it to different positions, and de-
- vices for controlling application of pressure medium to the hydraulic cylinders to control the blade movement.
15. In a bulldozer, a vehicle frame, a blade head at one end of and vertically adjustable relative to the frame, an upright blade support pivoted on the head for lateral swinging, a blade mounted by the support to be tilted to different working positions by a lateral, swinging adjustment thereof and having a hinged connection 10 with the support for angular adjustment relative to the direction of travel.
16. In a bulldozer, a tractor including a frame, a blade head disposed at one end of the frame, means rigidly supporting the head from the frame 15 and whereby it may be vertically adjusted, a blade mounting bar connected pivotally at one end to the head, means for adjusting its opposite end to different lateral positions, a blade hinge pin mounted by said bar lengthwise thereof, blade 20 sections mounted by said pin to extend laterally of the tractor and independently adjustable to different angular positions.
17. In a bulldozer, a tractor, a tractor frame, a blade head disposed at one end of the frame, 25 means rigidly supporting the head from the frame and whereby it may be vertically adjusted, a blade mounting bar connected pivotally at one end to the head, means for adjusting its opposite end to different lateral positions, a blade 30 hinge pin mounted by said bar lengthwise thereof, blade sections mounted by said pin to extend laterally of the tractor and adjustable to different angular positions, and a colter prow fixed to the bar across the hinged connection of the 35 blades.

FRANK H. LAMB.
